UNITED STATES PATENT OFFICE.

ALVA BAKER, OF PLATTSBURG, NEW YORK.

SASH-LOCK.

1,354,013.

Specification of Letters Patent. Patented Sept. 28, 1920.

Application filed May 1, 1920. Serial No. 378,144.

To all whom it may concern:

Be it known that I, ALVA BAKER, a citizen of the United States, residing at Plattsburg, in the county of Clinton, State of New York, have invented certain new and useful Improvements in Sash-Locks; and I do hereby declare the following to be a full, clear, and exact description of the invention, such as will enable others skilled in the art to which it appertains to make and use the same.

This invention relates to builders' hardware, and more especially to sash fasteners; and the object of the same is to produce an improved lock for holding the lower sash closed.

To this end the invention consists in a pivoted spring-actuated hook mounted on a plate adapted to be attached to the frame, and a keeper plate adapted to be attached to the top rail of the sash, the parts being of a specific construction as hereinafter more fully described and claimed and as shown in the drawings wherein:

25 Figure 1 is a vertical section showing this lock in place and the lower sash closed and locked thereby, and indicating in dotted lines the position of the device when swung aside so that the lower sash may be opened.

30 Fig. 2 is a cross section on the line 2—2 of Fig. 1.

Fig. 3 is an elevation looking from the left in Fig. 1.

The window frame F has an inner bead I and a parting strip or bead P, these strips being spaced to produce a channel in which travels the side rail S of the lower sash, and T shows the top rail and G the glass thereof. The upper sash is not illustrated herewith.

40 In the frame F is cut an opening 1 over which by screws 2 is secured a plate 3 having an upright slot 4 so disposed that its lower end shall stand about flush with the top of a keeper plate 5 which is counter sunk into the top rail T of the sash and held thereon by screws 6, this plate having an opening 7 beneath which the material of the rail T is cut away as at 8.

Below the slot 4 the plate 3 is provided with long and short ears 11 and 12 between which at 13 is pivoted a rightangular hook 14, its upright arm being continued above the slot into a stop 15 and continued and deflected below the pivot into a heel 16 which is connected with the long ear by a contractile spring 17. The horizontal arm 18 of

this hook projects through the slot 4 and has a downturned spur 19 adapted to drop through the opening 7 of the keeper plate 5, and the inner end of this arm is preferably 60 forked and carries an anti-friction roller 20 mounted therein on a horizontal pivot.

In Fig. 1 the sash is closed and locked. To unlock it the thumb is placed against the roller 20 and moved to the left so that 65 the entire hook assumes the position shown in dotted lines. This moves the spur 19 out of engagement with the opening in the keeper plate, and the sash is then raised by lifting it with the other hand. In its movement upward in the channel in the frame, its side rail S travels across the roller 20 and holds the hook in the dotted position. In the closing movement of the sash, as the end of its rail T and the extremity of the 75 keeper plate 5 pass downward across the roller 20, the hook is permitted to swing on its pivot 13 to the position shown in full lines in Fig. 1, and just as the sash reaches a completely closed position, the spur 19 80 drops through the opening 7 as seen. The sash cannot now be raised, because this spur projects downward from the horizontal arm 18 of the hook, whereas the body of the hook is pivoted in its support at a 85 point 13 considerably below the plane of such arm. Therefore in order to open the window again it is necessary to unlatch or swing open the hook manually, before lifting the sash, because if an attempt is made 90 to lift the sash without doing so, the spur will bind on the outer end of the opening 7.

One feature of this invention which will commend it to use is that it can be applied to a window already put up. To do so, the 95 beads I and P and the sash are removed, the opening 1 is formed in the frame F and the face of the latter cut away to permit the insetting of the upper and lower ends of the plate 3, and this plate and its hook and 100 spring are then applied and fastened by the screws 2. Meanwhile the keeper plate 5 can be easily applied to the top rail T of the sash. The parts are then restored, and the device functions as above described. 105

What is claimed is:

1. In a sash lock, the combination with a keeper plate adapted for attachment to the top rail of the sash near one end thereof and having an opening; of a rightangular 110 hook whose horizontal arm has a depending spur for engaging said opening, a roller

5 pivoted in the inner end of this arm, the vertical arm of said hook depending from the outer end of its horizontal arm, a supporting element for attachment to the frame, said depending arm being pivoted to such element at a point below the horizontal arm, and yielding means normally turning the hook on its pivot to throw its horizontal arm inward and its spur downward into engagement with the opening 10 in the keeper plate.

15 2. In a sash lock, the combination with a keeper plate adapted for attachment to the top rail of the sash near one end thereof and having an opening; of a right-angular hook whose horizontal arm has a depending spur for engaging said opening; a roller pivoted in the inner end of this arm, the vertical arm of said hook depending from 20 the outer end of its horizontal arm and deflected obliquely into a heel, a plate for attachment to the frame and having a slot for the passage of the horizontal arm and spaced ears through which the depending 25 arm passes, a pivot pin through said ears and this arm, and a contractile spring connect-

30 ing the heel with one of the ears and tending to turn the hook on its pivot to throw its horizontal arm normally inward and its spur downward, as described.

35 3. In a sash lock, the combination with a keeper plate adapted for attachment to the top rail of the sash near one end thereof and having an opening; of a right-angular hook whose horizontal arm has a depending spur for engaging said opening and whose upright arm depends from the outer end of the horizontal arm and is deflected into a heel and rises from said outer end into a stop, a plate for attachment to the window 40 frame and having a slot through which said arm projects and a pivotal support for its depending portion, and spring means between the plate and heel for swinging the horizontal arm normally inward, as described.

45 In testimony whereof, I affix my signature, in the presence of two witnesses.

ALVA BAKER.
